Inventor

Inventor

UNITED STATES PATENT OFFICE.

EDWARD E. CLEMENT, OF WASHINGTON, DISTRICT OF COLUMBIA, ASSIGNOR TO
EDWARD F. COLLADAY, OF WASHINGTON, DISTRICT OF COLUMBIA.

RADIO BROADCAST DISTRIBUTING SYSTEM.

Original application filed October 28, 1924, Serial No. 746,357. Patent No. 1,635,153, dated July 5, 1927.
Divided and this application filed May 2, 1925. Serial No. 27,514.

My invention relates to systems of radio broadcast distribution, and the present application is a division of my prior copending application, filed October 28, 1924, Serial No. 746,357 Patent No. 1,635,153, issued July 5, 1927. This invention has for its object to provide an organization for the broadcasting of intelligence in which orderly distribution may be secured, with maximum efficiency, and the entire service may be metered, whether local or long distance.

By means that will be described, it is contemplated to have national district and local programs made up day by day, from which any subscriber may select. Selection is determined by frequencies, which by the use of double modulation may be frequencies of the envelope or intermediate wave transmitted. At present not more than five such frequencies will probably be required for this purpose, although many more are available in the present state of the art, and the number will probably be increased as development proceeds.

Following the plan laid down in my preceding application, Serial No. 581,829 Patent No. 1,522,357, upon which Reissue No. 16,231 was granted Dec. 15, 1925, all supervision, metering, testing, and the like, which are individual to the subscriber, are done locally, that is to say, over the subscriber's telephone wire and either at his local telephone exchange, or at a local radio exchange associated therewith.

Certain lines of apparatus are developed and described in this specification, which so far as possible have been limited strictly to present standards of practice. It is to be understood that these are used for purposes of definition only, and not of limitation. Thus, while the entire system is built up of vacuum tube receiving and transmitting sets, other means may be substituted if and when the same becomes sufficiently reliable to meet the public need. All other changes and modifications which do not depart from the spirit of the invention are to be considered as contemplated thereby and included therein.

My invention is illustrated in the accompanying drawings, in which

Fig. 1 is a graphical diagram showing the channels of distribution and lines of authority and control in the system.

Fig. 2 is a circuit diagram of the same system.

Fig. 3 is a diagram of a telephone central station with two subscribers' stations connected to it and is intended to be read with Fig. 4.

Fig. 4 is a continuation of Fig. 3, and shows a radio central station and a radio subscriber's station physically connected therewith through the telephone circuits of Fig. 3.

Fig. 5 is a diagram showing the subscriber's double detector receiving set of Fig. 4 divided into two single demodulating units, one located at the subscriber's station and the other located at the central office, the first detector being at the subscriber's station and sending long waves through the subscriber's line to the second detector at central, which sends back audio waves to the subscriber's telephone.

Fig. 6 is a diagram showing a further modification of the circuit of Fig. 5, in which regeneration is added, at the subscriber's station, and the intermediate wave line coupling at central is included in the cord circuit.

Fig. 7 is a diagram of a further modification showing the said cord circuit provided with the same elements as in Fig. 6 except the battery which is in two units, one for talking and telephone signaling, and the other for the detector tube plate circuit.

Fig. 8 is a diagram showing a simplified form of metered system.

Figs. 9, 10 and 11 show respectively the daily program despatch sheet for the master or A station, a B station in the eastern time division and a local or C station in the same time division.

Referring to Fig. 1, the station A is shown connected by lines of distribution to district stations B', B², B³, and B⁴. The stations B' are in the eastern division, the stations B² in the central division, the stations B³ in the mountain division, and the stations B⁴ in the coast division. Each of these district stations is shown connected by lines of distribution to local distributing stations C in its district, and each of these local stations is shown connected to stations D typifying the ultimate subscribers' stations. The lines of distribution also represent telephone trunk lines from C stations to B stations. D represents the subscribers'

telephone lines which either terminate in stations C (if they are identical with telephone exchange stations), or are connected thereto, as indicated in Figs. 3 and 4.

5 It will be noted that in Fig. 1 not all the stations B are connected to station A by direct individual trunk lines, but some district stations trunk through a district master station, thus economizing trunk lines. Thus, 10 the trunks 58, 59, and 60 in Fig. 1 are shown extending to master district stations in the groups B², B³, and B⁴ respectively, other B stations in these district groups being connected to A through the respective master 15 stations B by relatively short trunk lines 61, 62 and 63. The number and routing of trunks so used is of course variable, and may be accommodated to the necessities of telephone traffic so as not to interfere with the 20 normal telephonic use of the wire plant, which is one of the cardinal points in the design of the present system.

A better idea of the general arrangement of circuits symbolized in Fig. 1 is conveyed 25 by Fig. 2, wherein a subscriber's line 18—19 (see Fig. 3) extends from his station A' to the central telephone exchange C which is equipped with line jacks J', connecting plugs P—P' and trunk jacks J⁵. From the trunk 30 jack J⁵, shown in the figure, a trunk line 50 extends to the district station B, which is also equipped with switchboard terminals including plugs P⁵—P⁶ and trunk jacks J⁶, J⁷. From the jack J⁷ shown in the figure a trunk 35 51 extends to the master station A where it terminates on a jack J⁸. The station is equipped with plugs P⁷—P⁸, and may be fully provided with telephone switching equipment, like the stations B and C. Details 40 of such switching equipment are shown in Figs. 3 and 4. In Fig. 2 operators' telephone instruments are shown at 81, 82 and 83, connected in the usual manner to the cord circuit, and these symbolize a complete 45 signaling and supervisory system. Each operator at stations B and A also has a demodulator and receiver for long IF waves, with suitable key for controlling the connection of the same to her cord circuits.

50 The radio equipment of station C includes a relay receiver and transmitter T with a local microphone and amplifier t² for local modulation. The antenna symbolized at 52 is supposed to receive waves sent out from 55 the B station of the district in which the particular station C happens to be located, and to which it is connected by means of the trunk line 50, which of course does not symbolize all telephone trunks but only such as 60 may be allotted for the so-called radio traffic. The frequency to which the antenna circuit 52 is tuned in that allotted to the C stations and to which they are all normally or permanently tuned. The antenna circuit 65 53 is for radiating modulated carrier waves

to the subscribers D in the particular local area surrounding and served by the station C under consideration. The frequency to which the antenna 53 is tuned is that allotted 70 to the subscribers D, and to which they are all normally or permanently tuned. The details of the subscriber's station apparatus, including both telephone and radiophone are shown in Figs. 3 and 4, wherein a particular station of class D is designated as A', and 75 will be described hereinafter.

Obviously, performances, or news, or other items of varied character which it is desired to broadcast either locally or over this entire system may be picked up in any 80 part of the same, and since it would be impossible to bring all artists, to, or to originate all matter at, the station A, there must be provision for ingathering as well as for distribution, or, stated in another way, the 85 system must be flexible enough to permit broadcasting from any part of it. It may be assumed therefor, without attempting to arbitrarily settle details of ultimate practice, 90 that all studio and other connections for broadcasting, should initially be made through a C station. Theoretically any subscriber's station having a telephone transmitter may thus become a broadcasting station, as disclosed in my prior copending application, Serial No. 746,357, Patent No. 1,635,153, hereinbefore referred to. Practically, while the subscribers' stations may be used as pickups, regular studio work will 95 probably always be done either through P B X boards with special equipment, or in other special stations connected with a C central station. All of these may be taken as symbolized by the station D or A' in Fig. 2. It should be noted in passing that this allocation or original modulation to C stations 100 does not interfere with direct broadcasting from A or B stations, since each of these can most conveniently be located at and operated in conjunction with a telephone central exchange which is also a C station or has a C station connected to it, as shown in 105 Figs. 3 and 4. Thus in Fig. 1 I have shown a microphone transmitter 64 at every station of the orders A, B, and C, to indicate 110 that broadcasting may be originated thereat when required. The actual manner in which this is now intended to be done is shown in Fig. 1. The symbolic station C is provided with a pair of jacks J¹³ and J¹⁴ between 115 which are connected the audio amplifier 65 and the intermediate frequency modulator and oscillator transmitter 66. The jacks J¹³ and J¹⁴ may be connected through the 120 operators' cords and plugs with the line jack J' on the one hand and with either one of the jacks J⁴ or J⁵ on the other. If jacks J⁸ and J¹³ are plugged together and jacks J⁴ 125 and J¹⁴ are plugged together, then the operation would be as follows: Assuming the 130

130

subscriber A' to transmit sound waves electrically over his line 18-19, these waves pass into the audio amplifier 65 and thence into the modulator 66, whereby a modulated intermediate frequency carrier wave is communicated to the input side of the relay transmitter T, which in turn modulates the long wave thus produced upon the short carrier wave allotted to stations D, and radiates the same from the antenna 53. Thus the station C is broadcasting on the common frequency wave, using an intermediate frequency which the subscribers can receive by double demodulation, in a manner to be presently described.

Now assume that instead of jacks J⁴ and J¹⁴ being plugged up together, the jacks J⁵ and J¹⁴ are so connected. The result will be as follows: The audio waves over line 18-19 pass to the audio amplifier 65 and thence to the modulator and oscillator transmitter 66 by means of which an audio modulated intermediate frequency carrier current is transmitted over the trunk line 50 to the station B. At this station an arrangement of jacks is encountered similar to that at station C. Jacks J¹⁵ and J¹⁶ have connected between them an intermediate frequency or carrier amplifier 67 which may be plugged up either for broadcasting from the antenna 55, or for continued transmission over the trunk 51 to the station A. To produce the first result, jacks J⁶ and J¹⁵ are plugged together and jacks J⁹ and J¹⁶ are plugged together, whereupon the carrier current or intermediate frequency carrier waves will be communicated to the input circuit of the oscillator transmitter B and thereby modulated on a high frequency carrier wave radiated from the antenna 55, at standard C frequency. This wave will be received and may be relayed by all the C stations within range of the transmitting station B. If wider distribution be desired the jack J¹⁶ is plugged onto the jack J⁷ of the trunk line 51, and the amplified or relayed intermediate frequency carrier waves are transmitted to the station A. Here the arrangement of the intermediate amplifier 68 between the jacks J¹¹ and J¹² is the same as that of the amplifier 67 at station B. By plugging up the jack J¹² to the jack J¹⁰, the amplified intermediate frequency waves will be communicated to the input side of the oscillator transmitter T² and thereby modulated on a short carrier wave and radiated from the antenna 57. As this wave has a frequency allotted to the B stations, all the B stations will receive it, and may in turn relay it to the C stations and they in turn relay it to their subscribers. One reason for the rule that all broadcast matters shall originate at or through a C station will now be apparent, viz: that the initial audio or telephone waves may be changed as near as

possible to the point of origin to modulated intermediate frequency carrier waves, which may then be imposed as modulations on a radiated carrier, or on a wire circuit, with equal efficiency. Audio waves in a wire circuit are subject to distortion to a greater degree than modulated superaudio frequency carrier waves. Also, by using superaudio frequency currents on the trunk lines, advantage can be taken of the well established systems of multiplexing and relaying already in use, and the trunks rendered more productive without interfering with their telephonic use. Thus, the initial audio waves are always changed into modulated superaudio waves at the nearest central station, and thence dispatched either on a carrier wave radiated from an antenna, or on a trunk wire to some other point where they are so dispatched.

In order to add still further to the flexibility of the system, the A station at the right of Figure 2 may trunk as from a jack or jacks J¹² through a trunk or trunks designated as X to any other part of the system, as for example to a particular B station, where the trunk X may terminate on a jack similar to J⁶ for connection to radio transmitter T', or by further trunking to some particular C station, and so to the radio transmitter T at such station, whereby matter can be picked up at any point and broadcast either generally or in a selected district or in a selected local area only. It follows also from this arrangement that when radio transmission is difficult over long distances or in any particular section of the system, due to seasonal or diurnal or non-periodic phenomena, the distribution by wire can be made to supplement distribution by pure radio and the average of efficiency maintained throughout the system. To accomplish this every part of the system must cooperate perfectly with all other parts as determined by the master control station A and district master control stations B, B', etc. both in time of transmission and maintenance of clear transmission channels. Such coordination may be compared to the system of train-dispatching on a railway system, and involves the use of interlocking records and time sheets, for A, B and C stations, and the management and dispatching of all radio traffic by a regular traffic force trained for that purpose. To fully understand this idea, the operating organization must be considered for a moment. First it must be taken into account that this system does not contemplate uncompensated or irregular use of telephone trunks and wire plant, but on the contrary is based on the assumption that the telephone companies, by contract or otherwise, will have a participating interest in all earnings of the radio broadcasting system, if they do not collectively act to operate it. The use of all wires and switching equip-

ment will therefore be paid for, and the cost of the service with a suitable profit will be distributed over the entire body of subscribers, and regularly collected by the local central station authorities by flat rentals or toll charges, both of which are herein provided for. Owing to the character of much of the work involved in operating, such as gathering, collecting, editing and allocating, the material to be broadcast as well as the attendant work of despatching and supervising the distribution of the daily program over the country, all of which is foreign to the normal service activities of a telephone organization, it would appear necessary to have a special operating organization, embracing the following: (1) Reporting and editorial department; (2) contract department, for artists and contributors; (3) engineering department, for regulation of methods and standardizing of apparatus, to work in conjunction with telephone engineering staff; (4) operating department, including routing, despatching and supervision; (5) business department, to receive and handle all matters of accounting, and in cooperation with the telephone organization, to fix charges.

Referring to Figs. 3 and 4, I have therein shown circuits of the central office and substation equipments and connections, Fig. 3 representing the telephone side of the system, and Fig. 4 the radiophone side of the system. Before proceeding to detail description it may be noted that in accordance with standard telephone practice, provision is made for keeping the telephone lines and central office circuits clear of all grounds or other disturbing connections during conversation. When the radiophone goes into service, by closing the filament switch its operation in receiving is identical with that of any radio receiver, and in the event that use is made of any transmission of waves over the line wires, as will be hereinafter pointed out, said transmission will be at a frequency above the limits of audition. In the present diagram, I have shown the circuits arranged with nothing but continuous current for radio purposes over the telephone line wires. This is the simplest form of control and the one nearest to present-day telephone practice, and is absolutely certain not to produce any disturbance in adjacent conductors in the telephone cables. Each radiophone set is provided with a cut off relay energized when the telephone set goes into commission, either by calling or being called, and at the central office whenever the radio operator takes control of the line, he disables it in the usual manner by pulling up the cut off relay at the telephone switchboard, this however being subject to the condition that a special tone test may be put on the radio board, and subject to interruption for telephone con-

nection. I prefer to use this tone test only with the radio operator's testing plug, because his regular connecting plug includes within its functions that of connecting a subscriber through the station amplifier to the broadcasting transmitting set, and a connection of this character should not be interrupted without permission.

Referring now to the diagram, Fig. 3, A and A' are two subscribers' stations connected by line wires 16—17 and 18—19 respectively to the central station C where they terminate on jacks J and J'. P—P' are plugs forming the terminals of a cord circuit 20—21, 22—23, having a bridged repeating coil I, the usual ringing and listening keys, supervisory signals s—s' and bridging connection to the main battery B. The same battery is shown supplying current to the line relays L, L', and through contacts at the cut off relays L², L³ to the respective lines for calling purposes. In this system, when a subscriber takes down his receiver, the line relay lights its lamp, which is extinguished when the operator inserts the answering plug. Battery supply for the connected lines is thereafter taken through the cord circuit 20—22, 21—23, in a manner well understood in the art. When the substation telephones are out of service, with their receivers hanging on their hooks, the line circuits are conductively open for direct current, leaving the ringers Q and Q' in circuit for alternating ringing current passing through the condensers q—q'.

Referring now to Fig. 4, it will be observed that the radio switchboard which I have designated generally by the letter R, is connected to the subscribers' lines by multiple taps marked 16^a, 17^a, and 17^b, and 18^a, 19^a, 19^b. These terminate on multiple jacks J², J³, corresponding to the multiple jacks on the telephone switchboard. It should be noted that throughout this system the tip wires 16 and 18 with their branches are connected to ground, while the sleeve wires 17 and 19 and their branches are connected to battery. This is extended into the radio side of the system for the purpose of securing proper balance between the main battery or power plant of that side and the main battery or power plant of the telephone side of the system.

At the subscribers' stations taps are also taken off from the telephone terminals to the radiophone terminals as indicated at 18^c, 19^c, and 19^d. (The radiophone is shown only at one substation for sake of simplicity of illustration.) The two branches 19^c and 19^d are taken from the sleeve or battery side of the line 19, and are connected to opposite terminals of the winding of a relay L⁴, which constitutes the substation cut off relay for the radiophone. The winding of this relay is bridged by a condenser q² through which

both ringing and voice currents can pass without substantial impedance. Where the radiophone is attached to a party line substation, this relay L^4 may be omitted, since 5 on such party lines there are usually grounds on one side or the other.

Normally, that is to say, when the telephone circuit is not in use, the cut off relay L^4 is deenergized and as a consequence the 10 wire 19^c is connected through a back contact of the relay through extension wire 24 to the branch 25 connected to the "A" battery marked A_1 in Fig. 4. The wire 18^c similarly passes through a back contact of the relay 15 to the extension wire 26 leading to test or listening relay 27 and ground. 18^c, it will be remembered, leads to the tip or ground side of the line, therefore it is the side which in the radiophone can be made use of with a 20 permanent ground or grounds, without disturbing the balance of the telephone circuit.

The radiophone receiver at the substation A' is shown as comprising an antenna 28, tuned coupler 29, first detector tube 30, tuned 25 filter coupler 33, second detector 31, audio amplifier tube 32, and audio transformers 34, 35, the last mentioned transmitting the amplified audio waves to the telephone receiver or loud speaker 36. The filament battery is 30 A_1 . The plate battery is B_1 and suitable tuning condensers and coils, tickler coil for regenerative effects, etc., are provided as required. I should remark in passing that 35 this representation of the radio receiver is intended to be typical only.

The relay L^5 has four pairs of contacts, one pair 27^a closing the wires 25 and 37 from battery A_1 to the filaments. The second pair 27^b closes the wires 25 and 38 so as 40 to put battery A_1 on the telephone transmitter T' , and through the induction coil I' , to ground. The third and fourth pairs of contacts 27^c, 27^d, close the wires 39 and 40, forming terminals of the secondary induction 45 coil circuit I' , to the tip and sleeve side of the telephone line respectively, through the back contacts of relay L^4 . The transmitter T' is shown hanging upon a hook switch H' controlling the connection of wires 41 and 50 42, constituting a parallel link between the battery A_1 and the filament bus 43. Thus the filament can be heated and the radiophone put in service either through the agency of the relay L^5 , or by the switch hook 55 H' . The former is controlled by the radio operator at central, and the latter by the subscriber at the substation. In addition to the hook, the subscriber has a manual switch h by which he can connect the battery 60 wire 42 through a wire 44 to his transmitter T' , coil and ground, so as to energize his talking circuit. I provide an ordinary telephone receiver t' in series with the secondary of the induction coil I' , and I interpose a 65 pair of condensers q^3 , q^4 between the second-

ary of the induction coil I' , and the receiver t' on the one hand, and the terminals of relay L^5 on the other, so that while the subscriber by means of switch h can connect his phone $T'-t'$ for receiving calls over the 70 telephone line, he cannot originate telephone calls thereover from the radiophone extension. This is subject to modification by omitting the condensers if desired to originate calls. 75

Returning now to the central station, and particularly to the radio department thereof shown in Fig. 4, T represents a broadcasting transmitter, symbolized in very simple form, but supposed to contain the usual elements of power supply, modulator, oscillator and aerial, with suitable amplification of the audio waves supplied on the input side. The jack J^4 connected to the amplifier t^2 and thence to the transmitter T , symbolizes a 80 group of such jacks or equivalent connecting means such as automatic switches, controlled by dials or keys for connecting any of the wire lines to said radio transmitter. Detailed appliances, both for the switching and 85 for the radio transmission, are well known in the art, and need no specific description, my present invention having to do particularly with the method of transmitting by wave radiation to the substations, and of bringing in all conversation originating or received at the substation radiophone over the subscriber's wire line. This includes repetition of modulated radio waves received at 90 the radiophone substation and also originating 95 messages gathered up and to be put through the amplifier t^2 on the transmitting T for broadcasting. 100

The cord circuit between plugs P^2 and P^3 in Fig. 4 is the same as the operator's cord circuit in Fig. 2, but the radio operator also has special test cords such as that shown in the upper part of the figure connected to plug P^4 . Here the keys $K-K'$ are of standard construction, as in the other cords, and the test contact of the plug P^4 is connected through suitable resistance to the supervisory lamp s^2 to the radio battery B' , means such as the commutator p^5 being provided to give special tone test on the test thimbles of the multiple jacks J , J' , J^2 , etc. It will be observed that the constant connection of the sleeve or battery wire 24 at the radiophone substation to the bus wire 25 of the battery A_1 produces charging of that battery by the constant flow of current therethrough from the main radio battery B' at the central office. The amount of energy thus delivered to the battery A_1 depends upon the size of the line wires, and the length of time available for such charging. As shown, the battery wire 24 is not cut off except when the cut off relay L^4 pulls up which is only when the line wire 120 is in use for conversation. 125

In Figs. 3 and 4, it has been assumed that the subscriber would employ apparatus for demodulating double modulated carrier waves, including two detector tubes, the first of which takes off the intermediate frequency carrier waves upon which the audio modulations are imposed; and the second of which takes off the audio frequency modulations from the IF waves. It is desirable to lessen the amount of apparatus at the subscriber's station, and at the same time give the central office operators an opportunity to supervise by "listening in" on any message being received, and to meter the service in a simple and efficient manner. For these purposes, I have shown in Figs. 5, 6 and 7 demodulating units located in part at the subscriber's station and in part at the central station, the operation being for the subscriber's unit demodulator to take off the modulated long or intermediate frequency waves and transmit them over his line wires to the central office where they are further demodulated by a cord circuit unit which is plugged on his line, (or the equivalent automatic switching apparatus). The second demodulator sends back audio frequency currents over the line wires to the subscriber's station, where they affect his ordinary telephone or any special form of receiver, including a table talker or loud speaker.

Referring to Fig. 5, the subscriber's station A' is equipped with a radiophone receiving device including an antenna circuit 28, tuned as usual, and coupled by means of coils 29 to the input side or grid circuit 125—126 of the detector tube 85. The input circuit may be tuned by means of condenser 129, but it is to be understood that this condenser and also the tuning elements in the antenna circuit may be adjusted once for all if the subscribers all work on a constant frequency, as hereinbefore set forth. The plate circuit 127—128 of the tube 85 includes one winding 123 of a tuned filter coupler, the other side of which 121 is connected to extensions 18^a and 19^a of the subscriber's telephone line circuit 18—19. The coil 123 is shunted by a condenser 124, and the capacity and inductance are so adjusted that the short circuit thus formed is resonant to the intermediate frequency waves imposed on the short carrier waves reaching the subscriber's instrument through the antenna 28. The variable condenser 122 is included in series with the coil 121, because of the line connection, tuning of the line being accomplished at both ends as will presently appear.

At the central office, the line wires 18—19 are connected to any desired number of answering and multiple jacks typified by the single jack J', and is provided with extensions 18^a—19^a passing to the radio department or radio switchboard R in the upper

part of the figure. The telephone jacks as in Fig. 3, are intended to be interconnected with other jacks for telephonic purposes through a standard cord circuit 20—21, 22—23, having terminal plugs P—P', and bridged by a common talking and signaling battery B, feeding through the two halves of repeating coil I and also feeding through a ring on each plug and test thimble on each jack to the cut off relay circuit 19^b, so that whenever a plug is in a jack of the line 18—19, circuit from battery to the cut off relay L^a will be completed and the line relay L' with its connection to the main battery B will be cut off and removed entirely from the line. In this cut off portion of the cord circuit are inserted supervisory lamp signals, s—s', adapted to be shunted by contacts controlled by supervisory relays included in the conductors 22—23, respectively. These relays respond to current in the subscribers' lines when they are interconnected, and the lamps light when the subscribers hang up their receivers.

On the radio switchboard R, the same line is provided with jacks typified by jacks J¹⁷—J¹⁸. As shown, these are in pairs, for convenience only, and to avoid putting a large number of contacts in one jack. The upper jack J¹⁷ is a duplicate of the telephone jack J', and has its contacts connected in parallel to the same conductors, respectively. Jack J¹⁸ is a radio jack pure and simple, and is connected to the same line wires 18^a—19^a through a tuned filter coupler composed of coils 115 and 117 and condensers 116 and 118. The elements 115 and 116 are employed in conjunction with the elements 121—122 at the subscriber's station to tune the line circuit to resonance at the frequency of the long waves sent forward as demodulated by the subscriber. The elements 116—117 at central are included in this figure between the line and the jack because by this means the tuning of the line can be made constant and adjusted once for all. The cord circuit adapted to cooperate with these twin jacks has corresponding twin plugs P¹²—P¹³ preferably connected mechanically so they can be inserted and removed from the jacks at the same time. The plug P¹² is the terminal of a standard talking circuit 90—91, with battery B bridged across it through coils 92—93, and provided with supervisory lamp 101, the controlling shunt therefor 102, the supervisory relay 103 and the talking shunt therefor 104, also with special test coil 106 supplied with a radio tone test through wire 108 from the commutator 107. When this plug is inserted in the jack J¹⁷ the cut off relay L^a of the telephone line is pulled up and the line cleared from all telephone switchboard connection, for radio use.

The plug P¹³ forms the terminal of a ra-

dio detector circuit, the tip and sleeve of the plug being connected through conductors 96-97 with the grid and the filament respectively of the detector tube 86. The plate circuit 97-98 of this tube is connected to the outside terminals of coils 94-95 which with the bridged coil 92-93 form the usual repeating coil connection between two ends of the standard bridged battery cord circuit. The battery B bridged between the windings 94-95, has its positive terminal connected to the plate through coil 94 and wire 98, and the conductors 97-98 are bridged by a conductor 99 containing a bypass condenser 100.

The result of this arrangement is as follows: The subscriber calls for radio service by moving his switchhook at station A', up and down rapidly. This flashes the line lamp before the telephone operator, who thereupon inserts the twin plugs P¹²-P¹³ into the jacks J¹⁷-J¹⁸. This pulls up the cut off relay L³, clears the line through from the substation to the cord circuit 90-91, 96-97, and thereupon, assuming that the subscriber has closed his filament circuit at the substation, radio waves received on his antenna 28 are demodulated, and their long wave or intermediate frequency component, carrying the audio modulations, is transmitted to line through the filter coupler 121-123. From line it passes through the filter coupler 115-117 and through the wires 96-97 to the grid circuit 97-95-B-94-98 of the tube 86. The varying potentials thus produced in the grid circuit of the tube are reproduced in current changes in the circuit 97-95-B-94-98. The superaudio frequency waves are absorbed by the circuit 99 and the condenser 100, and pure audio frequency waves are propagated through the repeating coil 94-95-92-93, into the telephone line circuit, through the plug P¹², the jack J¹⁷, multiple wires 18^a-19^a, and line circuit 18-19. At the subscriber's station these audio waves may be received on his ordinary telephone receiver *a*, or upon any special form of receiver desired.

Referring now to Fig. 6, I have shown therein a modification of the circuit of Fig. 5, in which the following features are introduced: First, I provide a feed back coil or tickler 130 at the subscriber's station; a special receiving telephone 133 with a terminal plug 132 adapted to be inserted in the jack 131 bridged across the telephone line outside of the filter coupler 121-123; and lastly I have removed the central office filter coupler 115-117 from its position between the line and the jack J¹⁸ as in Fig. 5 and instead thereof have located this coupler in a bridge of the cord circuit 96-97, thus doing away with the twin plug P¹³ and its connections. This also reduces the number of couplers required, and most impor-

tant of all enables the complete radio cord circuit to be used with any ordinary telephone jack, since the terminal plug P¹⁴ is an ordinary telephone terminal plug. For the reason stated, I have designated both jacks in this figure by the letter J', the lower one being at the telephone switchboard and the upper one at the radio switchboard. Both may be used interchangeably, or an ordinary telephone switchboard may be used for radio purposes without any change other than adding the filter coupler, the detector tube, and other connections to an ordinary standard answering plug cord. This interchangeability of the parts, makes it possible to give radio service on any telephone switchboard, using the same operators if desired, for both services. It also makes it possible to lengthen the life of a telephone switchboard, by rewiring the cords and converting it into a radio switchboard.

In Fig. 6, the antenna circuit 28 and the coupler 29 are the same as before; the grid circuit is 125-126, the plate circuit 127-128 includes a tickler coil 130, and the other parts have been referred to. At the central station the plug P¹⁴ is connected as in Fig. 5 to the repeating coil, battery, supervisory lamp, controlling relay therefor, tone test, etc. The coil 115^a of the central office filter coupler is bridged across the terminals of the plug, with its tuning condenser 116^a. The twin member of the filter coupler 117^a, with its shunting tuning condenser 118^a, is bridged through conductors 96-97 across the grid circuit terminals of the tube 86. The plate circuit 97-98 is connected to the repeating coil in the cord, and in this case also includes a tickler coil 134, which may be cut in and out of the plate circuit at will by means of a switch 98^c. This coil 134 feeds back into the grid circuit waves at intermediate frequency, as received over the line, and is intended to give a higher ratio of amplification in the audio current returned to the subscriber than would be possible without it. It should be noted however, that instead of thus using the regenerative principle, I contemplate employing radio and audio amplification in one or more stages of each, inserted between the detector tube 86 and the plug P¹⁴ or P¹² (Fig. 5).

In Fig. 7 I have shown a modification of the cord circuit in Fig. 6, which consists in providing a separate battery B² for the plate circuit 97-98 of the tube. This battery is located next to the plate, and the by-pass condenser 100 is bridged across the terminals of the repeating coils 94-95. This approaches more nearly to the common or standard method of connecting circuits than the bridge circuit of Figs. 5-6, and while probably not more efficient, is a little more flexible, as it permits the voltage of the B² 130

battery to be varied at will, without reference to the voltage of the battery B which according to telephone practice is constant at about 22 volts. Thus if amplifier tubes are used between the tube 86 and the coils 94-95, a separate plate battery would be required for the amplifiers, giving a higher voltage according to common practice. The operation of Figs. 6 and 7 is as follows:

19 The subscriber may call as before and in response to his call the radio operator gives him a cord circuit with terminal plug P¹⁴ or P¹⁵, whereupon his unit through the detector tube 85 demodulates the short wave carrier 20 received on antenna circuit 28, and sends the intermediate or long wave modulation thereof through the line wires to central, where it passes to the jack J' and the plug P¹⁴ and is repeated by the tuned filter coupler 115-21 117^a into the grid circuit 96-97 of the tube 86. Through this tube, and any amplifying tubes which may be employed, the audio modulations are first detected and then amplified and sent back through the repeating 22 coil to the plug P¹⁴ and the jack J' to the subscriber's line. At the subscriber's station they are received either on his regular telephone receiver, or on the special telephone 133 which typifies any kind of receiver which it may be found expedient and desirable to employ.

In the drawings, Figs. 5, 6, 7, I have not shown any amplification, but it is to be understood that any desired amount of amplification may be added between the detector tube 86 and the repeating coils 94-95. Such amplification may be of any known or suitable type, and needs no illustration. The cord circuits shown in Figs. 5, 6, 7 however, 40 with or without amplification, and thus adapted to give different classes of service, may be divided into groups, for which the subscriber should be charged different rates, as in long distance telephone service. It is 45 very necessary that there be metering upon which to base the charges, since the service is a time service and not a message service. For this purpose I contemplate including in each cord a meter actuator such as g' in 50 Fig. 5, which will operate the subscriber's line meter 301, which may be his telephone meter or a separate meter as desired, a number of times per hour determined by the class of service he is receiving. Thus 55 the No. 1 cord circuit may be connected to a commutator that closes the line meter circuit once every hour; No. 2 may have a meter actuator that works twice every hour; No. 3 may have an actuator that works three times 60 in the hour; while No. 4 may have its actuator work every ten or twelve minutes. The reason for selecting these time divisions is that the average charge per message for 65 telephone service is about five cents. At five cents per hour, and averaging three hours

service per day, a subscriber's radio bill would be \$4.50 per month. This is fairly comparable to the earnings of an average residence telephone for the same period, on a message rate basis. The fractions of time 70 could not be cut below a five cent value, unless a separate radio meter be provided for each line and it is desired to avoid this expense, as well as the upkeep of one hundred per cent of additional meters. In prior co- 75 pending applications Serial No. 581,831, filed August 14, 1922, Patent No. 1,522,359, granted Jan. 6, 1925, and Serial No. 583,560, filed August 22, 1922, Patent No. 1,522,367, granted Jan. 6, 1925, I have shown and de- 80 scribed metering systems which are suitable for use with the system of circuits herein disclosed, and in another application filed October 28, 1924, Serial No. 746,358, based upon the same system of circuits herein dis- 85 closed, I have disclosed and shall claim the adaptation of these metering circuits to the present system.

It should be particularly noted, that a subscriber, (which term is meant to include any user) may not keep his radiophone in service a full hour, a pertinent example being that of a man who desires to obtain a baseball score or other special information. A special provision should be made for 90 registering such service, as it involves all the elements of expense to the operating company which would be included in a much longer connection. For this purpose the operator may have a push button g connecting the actuating generator G direct to the meter circuit through the plug P¹³, as shown in one form in Fig. 5, together with the automatic actuating means for the meter, comprising the commutator g' which at 95 stated intervals connects the generator G to the wire 297 leading to the third contact on the plug P¹³, which when the plug is inserted in jack J¹⁸ completes the circuit from wire 297 through wire 298 to the cut off relay wire 19^b, thence to the high winding 299 of the meter LM. In Fig. 5 the meter is shown as the ordinary standard telephone line meter, which would thus serve a double purpose, registering both the telephone calls 100 and also the time of radiophone use in terms of telephone call units or telephone message units. Such a meter by reason of the high resistance in its winding 299 will not respond to the battery current which energizes the cut off relay L², but when the operator connects a generator as G producing current of higher voltage, then the meter magnet becomes sufficiently energized to attract its armature and close the circuit of its low winding 300, the rush of current through the low winding producing strong and certain actuation of the meter counting device 105 301.

By thus having the operator always press 110

the keys *g* immediately after making a radio-phone connection, there will always be made a base charge of one telephone message unit for the connection. If it should happen that the commutator close the actuating circuit immediately afterward, the meter would register two units for the first hour of use. If it should happen that the subscriber hang up in fifteen minutes the line would still bear the charge of two units for one hour. On the other hand, if the connection was made immediately after the commutator had closed the metering circuit, then no additional charge would be made for an hour, and if the subscriber should hang up within less than an hour, he would have only the one charge against the line. In any event, the charge would be safe to the company and fair to the subscriber as all public service corporations make a service charge if the measured rate charged is below a minimum amount. A commutator individual to each cord started when the cord is connected would of course register individual time use only.

The system shown in Fig. 8 is the same as that of Fig. 5 but simplified by omitting the radio broadcast distributing switchboard, giving the subscriber a simple radio receiving set of the single tube regenerative type and giving the telephone switchboard operator control of the metering of broadcast service.

Referring to the system of Fig. 8 more in detail, the subscriber's broadcast receiving set consists of a single tube radio receiving set BS of standard type with a set of head phones HT, and with no physical connection with the telephone line, but located at the substation A' for use by the subscriber therat. The subscriber's substation telephone apparatus and its line terminal apparatus L^a, J', etc. are the same as that of Fig. 5, except that the multiples 18^a, 19^a and 19^b extend only to other telephone multiple switchboard jacks, not shown, according to usual telephone practice. The operator's cord circuit terminating in the plugs P, P' is the same as that of Fig. 5 except that it is provided with a second metering key TM which is a telephone service metering key for actuating the line meter LM without actuating the cord circuit meter PM, the meter PM being used in this arrangement to record the use of the cord circuit for broadcast service. This use of the plug in connection with broadcast service consists in the connection of a subscriber's line, such as 18-19 of the substation A', through the cord circuit 20-21, 22-23 to a program announcement jack PJ connected with the program bus PB which is supplied continuously with telephonic announcements of program items available to the subscribers at their radio receiving sets which announcements carry

with them the proper instructions for tuning the subscriber's instrument.

In operation, a subscriber desiring broadcast service so apprises the operator by rapidly raising and lowering his switchhook which causes his line lamp L' to flicker and so immediately and directly indicate to the operator the character of service wanted, whereupon the operator inserts the plugs P' and P in the jacks J' and PJ respectively, connecting the subscriber to the program bus PB. The subscriber now receives, through his ordinary telephone receiver *a*, the announcement of the different program items available to him through his radio receiver together with the necessary instructions for tuning to each item or program of items. Having received such information, the subscriber may now hang up his receiver and immediately tune in on the desired program item without having to hunt and listen through parts of many different programs in order to get the particular item or items desired.

Each time the operator establishes an ordinary telephone connection she makes one momentary closure of the telephone meter key TM which actuates the subscriber's line meter LM to register one call, and each time a connection for program service is made she closes the broadcast service key *g* which actuates both the line meter LM and the program service meter PM to register one unit charge thus charging the subscriber and recording the special service use of the cord circuit. This enables the telephone exchange company to give metered broadcast service to the subscribers without physical connection of broadcasting apparatus to the telephone circuits, to keep a record of the total amount of such special service rendered and to meter the service to the subscribers individually.

The station A can either broadcast direct or by wire trunking through the B stations, preferably the head B station of each division. It is further to be noted that the A station when so working over wire trunks can receive the same waves radiated from B or antenna 56 (Fig. 1) and by demodulating and the listening to the audio frequency component thereof can determine the efficiency of transmission and the tuning of the B apparatus with respect to the short carrier wave employed.

Each station B is supposed to be a district station, that is, it compiles and checks up all bookings or "regular number" items in its district, keeps the A station informed thereof, makes up district programs, supervises local or C programs including items to be recorded and released later, receives, records and forwards traffic reports and charges from its district to A and acts as a relay station for mixed wire and radio trans-

mission between the C stations in its district and the rest of the system. The relation of the B and C stations to each other and their operation will be better understood after an explanation of the last sheet of drawing herein, containing Figs. 9, 10 and 11, as well as a statement of the manner of employing primary and intermediate frequencies for distribution without interference. First, however, the functions of the C stations should be fully understood. These are the stations which come into immediate contact with the subscriber, and which for transmission purposes form their immediate source of supply. So far as the general broadcasting goes, these stations will be largely considered as they are described in Patent No. 1,522,357, viz as relay or distributing stations, each for its own local area. In speaking generally of these stations it will be understood that they may or may not be identical with the telephone central stations for the same areas. In the majority of cases each radio C station will be one of a group of telephone exchange stations in its area, and will receive communications from all parts of the area except its own particular territory, by trunking. As there are approximately 10,000 telephone exchanges in the United States, of which approximately 5,000, it may be estimated, will be available as C stations in this system, the importance of having them properly organized and related to each other as well as to the subscribers will be apparent. The functions of each radio exchange C include the following: Relay broadcasting on the subscribers' or D carrier wave frequency of program items originating at B or A stations; selection of items and arrangement of local programs to include approved local items if any; listening in and supervising reception by subscribers, using the wire lines for this purpose; connecting subscribers' wires or studio wires to trunk lines for direct communication or preferably through amplifier modulator and transmitter units 65 and 66, for superaudio carrier current transmission over trunk lines 50 or to local broadcasting transmitters T as indicated in Fig. 1; rendering special service by broadcasting out with wire return, for special groups of subscribers holding meetings and the like, using special carrier-wave frequencies, or special intermediate frequencies for this purpose; metering all service, regular or special, and billing same, preferably through the financial department of the associated telephone operating company, installing, inspecting, testing and maintaining subscribers' station equipment; and compiling, editing and publishing in the press, by wire, and otherwise, of the radio programs for the local area served.

A brief review of these functions will

show the advantage in reduction of expense and added efficiency to both the telephone and the radio administrations of combined operation. In the single matter of metering and billing, it is to be noted that since provision is herein made for metering the radio service on the telephone line meters, a single reading, billing, mailing and collecting will suffice for both services. In the matter of postage alone, since two cent stamps are employed in mailing telephone bills, the saving in a city of 10,000 subscribers would amount to \$200. a month or \$2400. per annum; and the countrywide postage saving on the basis of estimated present radio use would amount to \$40,000 per month or \$480,000 per annum. The cost of labor for performing the functions mentioned would be many times this amount, so that by the use of the system herein set forth, it may be estimated that several million dollars per annum of overhead expense will be saved, as compared with separately operated systems, or to put it another way the wire plant will show a large addition to its earnings by the reduction of overhead, entirely aside from direct payment for the radio service. If we assume a district with one B station and 99 C stations located therein, serving approximately 100,000 subscribers, the combined saving on overhead, without any direct earnings, would amount to more than \$125,000 per annum, which while perhaps insufficient to pay interest on the capital invested in broadcasting apparatus, would carry all ordinary expense of broadcast operation.

For the selection of items and arrangement of local programs, the operation of station C would be regulated according to the daily dispatch sheets of the A and B stations, (see Figs. 9 and 10) and the number of primary or intermediate frequencies available, which will be presently explained.

For listening in and supervising reception by the subscribers, the radio station C makes use of the apparatus shown in Fig. 4, whereby the waves radiated from the transmitting station may be caused to return after demodulation over the wires so as to be audible to the operator through a proper listening apparatus. The apparatus of Fig. 4 also includes elements such as V, P⁴, etc., for testing the subscriber's line and instrument. If local batteries are employed at the subscribers' stations, their condition and voltage can be ascertained and if all current is supplied from central as in my prior applications, Serial Number 699,023, filed March 13, 1924, and Serial Number 722,993, filed June 28, 1924, then the resistance of the circuits and their proper tuning can be determined.

For connecting subscribers' wires or studio wires to trunk lines for direct or telephonic communication the radio operator has cord

circuits and terminals of the lines, symbolized at P^s , J^s , J^2 , etc., in Fig. 4 and may have equivalent automatic or semiautomatic switching apparatus. The operation is symbolized in Fig. 1, which shows J' and J^s by means of which the subscriber A' can be trunked to any part of the system without going through the telephone switchboard.

I have shown the subscriber's radio receiving set in Fig. 4 as provided with an extension telephone $T'-t'$, and by means of these and the separate switching apparatus under control of the radio operators it is to be understood that all radio operations, including incidentally telephone trunking or interconnection between radio subscribers can be handled by the radio switchboard, without access to the telephone switchboard or the telephone operators, (except in cases where 20 the same switchboard is employed for both classes of service). I believe this to be original with me and shall claim the same accordingly. The typical and preferred mode of trunking by wire in this system, 25 however, is by means of modulated superaudio frequency carrier current which can be interchangeably imposed on the wired circuits or upon suitable radio frequency carrier waves so as to render transmission and 30 interchange over and between the elements of the mixed system both simple and flexible. This is accomplished by first of all modulating the secondary intermediate frequency in accordance with the sounds which 35 it is desired to transmit; and then sending this modulated carrier current over the trunk circuit or circuits to the point where it is to be utilized. It is to be understood that in such wired transmission of relatively high 40 or superaudio frequencies, the line and trunk circuits are appropriately tuned, as indicated in Figs. 5, 6 and 7. It is also to be understood that when transmitted over long trunks, the carrier currents may be relayed 45 and amplified and may be passed through filter circuits when required, all according to principles which are well understood in the art, and which have not been illustrated herein as they form no part of the present 50 invention. Thus, for example, in assuming a trunk connection from the head B stations in Fig. 1 to the master station A, it is taken for granted that the wire trunk lines employed for this purpose may be multiplexed and provided with tube relays and amplifiers, the same as at present. If more than one intermediate frequency is assigned 55 to the radio broadcasting corporation for use on wired trunk lines, all such frequencies of carrier current might be confined by agreement to the same trunk or trunks, or if a more flexible agreement were possible, it might be applied over any trunks in the system. This is a detail of administration 60 to be worked out and agreed upon between

the telephone company and the broadcasting company; but the principles involved of having certain frequencies or bands of frequencies which can be separately allotted for radio uses only over a system of wired trunk 70 lines, I believe to be original with me and shall claim the same accordingly. This is not to be confused with telephone trunking broadly, even though it be employed for transmitting sounds from a distance to a 75 radio broadcasting studio. The combination I present is more flexible than that, and at the same time more comprehensive, because it includes all the elements of an organized system, whereby modulated intermediate carriers may be forwarded either by means of wires or by means of double modulated carrier waves, from any point in the system to any other point in the system, 80 without losses or distortion due to changes in frequency or tuning. It will be remembered that for receiving purposes the instruments at subscribers' stations are all supposed to be standardized and tuned to one fixed frequency. (This of course is subject 85 to distribution of carrier wave frequencies as expediency may determine and as recommended by the Government. For general purposes it may be assumed here that all subscribers' instruments are tuned fixedly 90 for the same primary carrier wave frequency.) In passing through the relay stations however, the primary carrier wave frequencies change from A to B, from B to C, and from C to subscribers D. Thus, if the 95 sending station B should vary the frequency of the C carrier wave transmitted, this would not affect the intermediate wave frequency or the audio modulations, and so long as C uses the proper frequency F, for the subscribers, the original intermediate waves 100 formed and modulated at the point of origin, would be available in the subscriber's tuned local circuit.

For metering the service, the arrangement shown in Fig. 5 is typical of a number of such arrangements that can be employed, but all of this work is done at the C stations, so far as the subscribers are concerned. I do not specifically claim the metering circuits and apparatus herein, the same being described and claimed in copending applications, Serial Number 581,831, filed August 14, 1922, Patent No. 1,522,359, granted Jan. 6, 1925, Serial Number 583,560, filed August 120 22, 1922, Patent No. 1,522,367, granted Jan. 6, 1925, Serial Number 691,825, filed February 9, 1924, and Serial Number 732,797, filed August 18, 1924, Patent No. 1,627,332, granted May 3, 1927.

In Fig. 5 I have shown an automatic commutator g' and an operator's key g for connecting the metering generator in the local or cut off circuit 19^b to a line taking radio service, so that the telephone line meter LM 120

- may be energized at intervals determined by the speed and construction of the commutator g' . By this method, radiophone time use is charged for in telephone call units.
- 5 The adjustment of relative unit values between the radio use and the telephone use is not attempted as a finality, because it will be determined by some mutual adjustment owing to the necessity for distribution of 10 profits. In other words, if the telephone rates come down because of increased earnings through the radio service, then the rate of charging in telephone call units for radio service will have to be increased, in order 15 to maintain a parity. Such a result is likely to follow the introduction of combined service, such as herein described.

Where all recording is done on the same meters, as in Fig. 5, it has already been 20 pointed out that reading the meters, recording, bookkeeping, billing and collecting can all be performed by the same force and at the same expense required for telephone service alone. The savings by this method 25 have also been pointed out. Several other aspects of this point are to be considered, including the metering or recording of service between central stations and the allocation of charges based thereon; the proper 30 division of gross receipts, as between the telephone administration and the radio administration; and the separation of radio and telephone charges in monthly statements to the subscribers when the subscribers demand it, or where it is required by law. 35 These points will be further discussed presently.

The installing, inspecting, testing and maintaining of subscriber's station equipment is all for the C stations. It should 40 be pointed out however that where a subscriber's telephone line terminates in a telephone exchange different from that which constitutes or is associated with the C station 45 for that area, maintenance, equipment, testing, etc. would be for the nearest central station, by preference, whether a broadcasting station or not. There is another reason 50 for this, viz: that the subscriber looks to his own central station for maintenance of his telephone instrument, and it is good practice to unify and not divide in cases of this kind. For this reason, if the radio administration be in the hands of a separate corporation, 55 the actual physical work in connection with the subscriber's station and line equipment, would be in the hands of his local wire exchange. It might be added that to be constant, and in accordance with the 60 best practice, all subscribers' station equipment should belong to those who install it, viz: the telephone companies. The radio corporation gives programs, operates the central office equipment, but for this purpose 65 preferably rents or leases the wire switch-

board instrument equipment from the telephone company. The great advantage of this will appear in connection with the discussion of charges and finance.

As records compiling, editing, and publishing of the radio programs, this is necessarily in the hands of the C stations for their respective areas. Nation wide announcements may be briefly broadcasted over the entire system, local announcements may be 75 similarly broadcasted from B stations and C stations respectively; but time, service, and copper are all too valuable in an organized system, to make any sufficient announcement of regular programs. These should 80 be determined far enough in advance as indicated by the daily dispatch sheets as shown in Figs. 9, 10 and 11, to be interchanged by mail or by wire reports run through at times when the wires are otherwise idle. Artists 85 and performers or lecturers are booked up at A, B and C stations respectively, according to their national, divisional, district or local value. These bookings may be divided into several classes, as for example: 90 (a) permanent attractions, including artists and musical organizations of established standing, lecturers, etc. These have permanent numbers on all the dockets of the A, B and C stations, and can be used in forming permanent programs days, weeks or months ahead. (b) temporary attractions, due to 95 public notoriety, or some other interest. These get star numbers on all dockets, and according to their rank, of national, district or local, they are inserted on programs by A, B or C stations, respectively. (c) news 100 items, and other purely ephemeral matters of interest only at the moment, which are not carried on the dockets, except as blanks to be filled, which blanks however may be given regular numbers for convenience in wire communications. (d) emergencies and 105 disasters of such character as to have the right of way over all other items. These are not booked, but may be carried in blanks as by the press associations. For example, 110 photographs and other materials concerning prominent people, occasions, etc., locations where earthquakes have occurred and may occur again, etc., are kept in order, are kept up to date, and numbered permanently for radio reference. (e) events of national importance, and affairs of the National Government. These cannot be docketed, but are 115 carried with a double star, and preferably given one number which suffices to clear the air and if necessary take over the entire system with or without notice.

From the foregoing, it will be evident that 120 communication with the subscribers is from the C stations, not only in broadcasting and over telephone lines, but through the press and by the means of advertising. Nevertheless, according to the nature of the items 125 130

which are certified to the C stations for their use, either by relaying or direct, approval of A or B stations must be obtained before varying any part of the main program.

5 Returning now to the questions of metering and finance, as between the radio administration and the telephone administration particularly, the first question to be considered is how to satisfy the subscriber who 10 demands a division of his radiophone and of his telephone accounts. The simplest method is the best, and that which presents itself as the most available is also one of the earliest methods of metering known in the 15 telephone art. This is to provide a simple counting device at the subscriber's station stepping around a number device or devices as in a Veeder counter. Meters of this sort actuated by the switchhook of telephone instruments are well known in the art; and a 20 Veeder counter of this type may be attached to any form of switch adapted to control the radio receiving instrument. By providing 25 this counting instrument with a stepping magnet included in the radio battery circuit from central, a momentary break in the line made simultaneously with the closure of the line meter at the radio switchboard, would actuate the subscriber's meter so that it 30 would show the time use of his radiophone, in telephone message units. Another method is to apply the counting meter to the subscriber's telephone instrument, instead of the radiophone so that it will record his telephone calls in exactly the same manner as 35 the line meter at the central station. To do this, the meter must register additional units for messages exceeding the three minute or other minimum length of time, which is now 40 quite generally fixed in exchanges throughout the country. One way of accomplishing this is to make the operator's key in the telephone cord circuit of the subscriber's answering operator, momentarily send high potential 45 current from the usual meter generator G_t (see lower part of Fig. 5), to lines as well as through the central office meter circuit. To take advantage of this the high wound meter magnet at the subscriber's station 50 might be connected across the line while the subscriber is talking only.

Another, and a preferable method if the matter of expense be disregarded, is to duplicate the line meters LM (Fig. 5) at the 55 central station, providing each line with one meter for telephone calls, and another meter for radiophone calls or time use. In such case the wire 19^b would have to be duplicated, so that the radio meter would have its 60 own separate wire loading from the test thimbles of the radio jacks J¹⁸. The twin plug arrangement of Fig. 5 would be eminently suited to this arrangement since the 65 wire 298 would then pass parallel to the wire 19^b, and connect with the winding 299

on a separate radio line meter, without other change of the circuits. The objection to this arrangement is the cost of installation, and the double cost of maintenance.

Assuming, then, that the two services are 70 separate, but switchboard and other operation requiring technical handling to be in the hands of the wire company, it is obvious that periodical accountings must be had. For this purpose, it is necessary to 75 know the total time use of the radio service of each class, and the total use of the telephone service for the same period. For a general accounting, details would not be necessary. Thus, a message meter of the 80 type LM in Fig. 5, for each operator's position of the switchboard herein typified, and having a branch from its coils 299—300 to the meter button of each one of the cord circuits on its position, would record all the 85 telephone calls, including extra charges on that position, it being evident that an operator would not press two meter buttons at the same instant. This is indicated in Fig. 5 at PM, which designates a position meter 90 reading in totals of calls of that position.

Inasmuch as the recording of two classes of service on the same telephone line meter is new, the necessity for distributing charges recorded is also new, and I believe the arrangement thus specified to be original with me and shall claim the same accordingly.

Parallel means for metering the total station load may be in the form of a Bristol recording time sheet, taken from a station meter connected in the main bus circuits so as to record the total current consumption for the station. I propose to use this principle for a check against the message meter record in effecting settlement between the 100 radio administration and the telephone administration in this system. Telephone use may be ascertained by position meters, as above stated, and is recorded in message units each equivalent to one three minute 105 conversation. Radio time use might be separately recorded in this way, using a position meter, or a meter of the type LM for each cord or connective circuit on the radio switchboard. I consider it preferable 110 however to connect a recording ammeter in the main battery bus connection to the supervisory lamps (see 105 of Fig. 5) or some other piece of apparatus which has a constant resistance and a constant current flow. 115 This is indicated at PM and RM in Figs. 5 to 7 inclusive. I have also indicated in Fig. 3 a station meter to record the total current flow through the lamps s' or their shunt circuits for telephone connections, thus making a parallel record to that of the radio service. By plotting the curves thus developed on straight line section sheets, a direct comparison between the total radio time use and the total telephone time use can be 120 125 130

made with reasonable accuracy as a check against the position meters and the line meters above described. I believe all of this arrangement for divisional accounting with separation of two services metered in common, to be new and original with me, and shall claim the same accordingly.

Accurate metering of the radio service is of great importance, aside from the matter of charges based thereon. As hereinbefore stated, the telephone load curve has a fairly constant characteristic shape, with very well developed peaks at certain hours and valleys at certain other hours. In order to take full advantage of all of the benefits resulting from combined wire and radio operation, and especially in order to realize all the profits that should rightly flow from such an economical administration of the wire plant, the radio traffic load curve must be adjusted to the telephone load curve, and careful studies made of the reactive effect of each service upon the other. Thus, it may be expected that to a certain extent use of the telephones will be modified when the use of the radiophone becomes organized and habitual; and similarly where the radiophone and the telephone are associated together, the use of the radiophone will frequently be postponed until times when the telephone is not in use, and vice-versa. In advance of any accurate body of data however, by which careful comparisons can be made, it is possible to take existing telephone traffic curves and apply assumed radio traffic curves thereto, with a view to showing what can be accomplished, and deducing what may be further expected by way of regulating and regularizing the radio traffic, and the telephone traffic incidentally. This is fully discussed in my copending application, Serial No. 746,357, Patent No. 1,635,153, granted July 5, 1927, of which this is a division.

Referring now to Figs. 9, 10, and 11, I have shown therein daily dispatch sheets for stations A, stations B and stations C. It has been explained that each of the stations A, B and C will keep a docket or entry book containing the list of detailed contributors in general to the radio program, each artist or attraction being indicated by a serial number. These numbers will be fixed for all permanent attractions, for convenience in making up programs and also in making reports by wire or otherwise. Up to this point, I have said nothing about the distribution of programs by means of intermediate frequencies, and so it will be understood that these daily dispatch sheets are primarily designed for a system in which the A station transmits on a characteristic primary wave frequency to each of the four divisions, where the master B station has means to reach all the other B stations, as

well as its own district C stations direct. It is not necessary that the head B stations should receive and relay the A program, but the B stations in general distribute on such distinctive wave lengths as may be allotted to them to the C stations, and they in turn to the subscribers. Thus, the dispatch sheet of Fig. 10 can be made up in part from the items selected from the A dispatch sheet shown, and in part from matter originating at station B and indicated by book numbers of the B stations. The same procedure applies to transmission from the stations B to the stations C, the program shown on the daily dispatch sheet in Fig. 11 being made up in part of items received through B from A, in part of items originating at station B and in part of items originating at station C. Various combinations of primary frequencies and intermediate or secondary frequencies can be employed for enabling selection to be made, and the number of simultaneous elective programs that can be put out by any one of the three stations A, B, and C is limited only by the number of transmitters with which they are equipped, and the number of intermediate frequencies available to which they are respectively tuned.

Coming to the subscriber's station, the primary wave frequency which he receives is fixed, but referring to Fig. 4 it will be observed that the filter coupler 33 shown between his first detector 30 and second detector 31 is provided with variable tuning elements, as are also his antenna circuit 28 and his local input circuit 43. The subscriber may therefore select intermediate frequencies by merely tuning his filter circuit 33. In tuning, both sides must match up as well understood by those skilled in the art. Thus, initial distribution by station A on several frequencies simultaneously results in selection at station B and relaying of the selected items, plus addition of original items, on several frequencies, all of which afford station C the opportunity of selection plus the addition of original matters, for relaying and transmitting to the subscribers D; while the subscribers in turn by tuning their intermediate wave filter circuits can select any and all of the items desired and reject the others. It is of course possible for all the modulated frequencies at A to be relayed from B to C and from C to the subscribers, using whatever number of primary frequencies and intermediate frequencies are available. This might actually occur when a national program was being carried on which must be condensed in point of time, requiring the transmission of several items at once, from which the ultimate subscriber must select those which he would prefer to hear. I consider this arrangement and the method of operating relay stations

in an organized system for purposes of selection of program to be new and original with me and shall claim the same accordingly. This applies as well to subscribers' stations as to the intermediate and A stations, and to the entire system as such.

It is of course understood that any or all of the details, construction and operation thus outlined may be changed and modified as necessity, convenience, and the resources of the art from time to time may dictate or permit, without departing from the scope and purview of my invention. I believe I have disclosed a complete and operative system for the purposes described, which is novel in totality, as well as in its several divisions and parts, and that the methods employed throughout are novel, when considered in an organized system. I do not claim the specific circuits shown except as hereinbefore stated, but I do claim the system of the parts and the method of operating the same, as herein disclosed and I wish it distinctly understood that I contemplate all non-essential changes and modifications which may be made therein.

While the master station has been described as being located near the geographical center of the system, it may be permanently or at times located in any division, for example, at New York in the eastern division, controlling other divisions by wire or by radio relaying repeated from division to division. The master station, wherever located, is for the time being the center of the system.

What I claim is:

1. A general organized radio broadcasting system comprising originating and relay stations and subscribers' stations, adapted to distribute radio broadcast over a wide area, with uniform efficiency, and local means each adapted to group the subscribers in one local area, said means including control of the distribution in its area, and means for metering the entire radio service received by each individual subscriber from originating and relay stations as well as the local area.

2. In a combined telephone and organized radio broadcasting system, telephone exchange centers in local areas of the general broadcasting field, subscribers' radio receiving equipment and telephones, related to said telephone centers by wire lines, common means at said telephone centers to meter the individual subscriber's use of both his telephone and his radio receiving equipment, and centralized means for recording the two classes of service separately in comparable units.

3. In a combined telephone and organized radio broadcasting system, telephone exchange centers in local areas of the general

broadcasting field, subscribers' radio receiving equipment and telephones, related to said telephone centers by wire lines, common means at a telephone center to meter the individual subscriber's use of both his telephone and his radio receiving equipment, in terms of normal or base charge telephone conversation units, and other means at said telephone center to meter collective telephone use by all subscribers in the local area.

4. In a combined telephone and organized radio broadcasting system, telephone exchange centers in local areas of the general broadcasting field, subscribers' radio receiving equipment and telephones, related to said telephone centers by wire lines, common means at said telephone centers to meter the individual subscriber's use of both his telephone and his radio receiving equipment, in terms of normal or base charge telephone conversation units, and separate means acting on said metering means to predetermine a fixed charge for each radiophone use regardless of time.

5. In a combined telephone and organized radio broadcasting system, telephone exchange centers in local areas of the general broadcasting field, subscribers' radio receiving equipment and telephones, related to said telephone centers by wire lines, common means at said telephone centers to meter the individual subscriber's use of both his telephone and his radio receiving equipment, in terms of normal or base charge telephone conversation units, means to vary the ratio of such unit charges for radio service according to the class of service, in each instance, and means associated with the radio broadcast distribution to subscribers for repeating the recording of such units a number of times proportioned to the subscriber's time use of his radio receiving equipment.

6. In a combined telephone and organized radio broadcasting system, telephone exchange centers in local areas of the general broadcasting field, subscribers' radio receiving equipment and telephones, related to said telephone centers by wire lines, common means at said telephone centers to meter the individual subscriber's use of both his telephone and his radio receiving equipment, said means including a line meter recording telephone conversation units, and independent means operable in giving telephone service and in giving radio service, respectively, to actuate said meter in common, together with separate means to record total use of both services, as a check on the individual count.

7. In a combined telephone and organized radio broadcasting system, telephone exchange centers in local areas of the general broadcasting field, subscribers' radio receiving equipment and telephones, related to

said telephone centers by wire lines, common means at said telephone centers to meter the individual subscriber's use of both his telephone and his radio receiving equipment, 5 said means including an individual telephone line meter for each line, means operable in giving radio service and independent means operable in giving telephone service, both actuating said meter, and a group or position 10 meters connected at each group or position in the telephone switching equipment to record all calls completed and conversations individually metered for that group or position.

15 8. In a combined telephone and organized radio broadcasting system, telephone exchange centers in local areas of the general broadcasting field, subscribers' radio receiving equipment and telephones, related to said telephone centers by wire lines, common means at said telephone centers to meter the individual subscriber's use of both his telephone and his radio receiving equipment, 20 consisting of individual line meters and independent actuating means therefor operable in giving telephone service and in giving radio service respectively, with station meters for recording the separate radio and

telephone uses in bulk, for traffic and settlement purposes.

9. In a combined telephone and organized radio broadcasting system, telephone exchange centers in local areas of the general broadcasting field, subscribers' radio receiving equipment and telephones, related to said telephone centers by wire lines, common means at said telephone centers to meter the individual subscriber's use of both his telephone and his radio receiving equipment, 30 and individual means to meter the subscriber's telephone calls separately.

10. In a combined telephone and organized radio broadcasting system, telephone exchange centers in local areas of the general broadcasting field, subscribers' radio receiving equipment and telephones, related to said telephone centers by wire lines, common means at said telephone centers to meter the individual subscriber's use of both his telephone and his radio receiving equipment, 40 and individual means at subscribers' stations to record telephone calls separately.

In testimony whereof I hereunto affix my signature.

EDWARD E. CLEMENT.
